[57] CLAIM

The ornamental design for a double chain collar keeper,
as shown and described.

DESCRIPTION

FIG. 1 is a front elevational view of the invention;
FIG. 2 is a top plan view of the invention which is the
same as the bottom plan view;
FIG. 3 is a side elevational view of the invention; and,
FIG. 4 is a partial rear elevational view, with part of the
collar keeper removed for ease of illustration, the por-
tion not shown being a mirror image.

Fig. 3.
